FEEDING AND ALIGNING DEVICE

Beulah Louise Henry, New York, N. Y.

Application April 2, 1937, Serial No. 134,467

28 Claims. (Cl. 197—127)

This invention relates to typewriting machines, and more especially to an improved means for feeding superposed sheets in aligned or properly collated relation.

5 Because of slippage between record sheets or strips it has heretofore been proposed in the feeding of a continuous series of collated and superposed forms to provide marginal holes in the sheets to receive pins carried either by the main typewriter platen or by some separate roller. Many of these proposals have been embodied in commercial machines and have been used with considerable success. Machines of this character, however, are open to the objection that the record 10 sheets used therewith must be specially prepared by preforming the marginal holes therein. This practice not only adds appreciably to the cost of the sheets but renders them unsightly.

It is therefore an object of the present invention to provide a writing machine especially adapted for use with a continuous series of collated and superposed record sheets in which the need for preformed marginal holes is eliminated and in which the collated forms are positively fed relative to the printing line in alignment and registry.

It is a further object of the present invention to provide a feeding and aligning device which may be manufactured economically and be easily added to typewriters and the like already in use.

In achieving this object the present invention contemplates the provision of feeding and/or locking instrumentalities which may be supported on the usual paper lock bail, and controlled or 35 actuated by a simple mechanical connection to the usual platen shifting lever.

Many of the previously proposed means for positively feeding sheets and maintaining them in registry were large and cumbersome, and 40 often greatly impeded the regular feeding of the sheets toward or away from the platen.

Therefore, it is an important object of the present invention to provide a feeding and aligning device which will not impede the regular feeding 45 of the sheets toward or away from the regular platen, and which may be easily and quickly moved to operative and inoperative positions relative to the platen.

One feature flowing from the attainment of this object is the provision of feeding and locking means entirely clear of the inlet, entrance or starting side of the platen. A complementary feature is the provision of a manual control for raising 50 the locking means from the platen and sheets

thereon, without moving the entire feeding and aligning device into an inoperative station.

Some of the previous proposals were in the nature of large rectangular frames with much supplementary mechanism rigidly secured to the 5 regular platen carriage; but, the considerable added weight imposed by such supplementary mechanism on the carriage increased the energy required to operate the typewriter, and made the machine less responsive or slower in operation. 10

It is an object of this invention to overcome these shortcomings.

Features of this invention resulting from the attainment of the last mentioned objective are the provision of a simple mechanism consisting 15 of very few small and lightweight parts preferably carried by the usual paper lock bail.

A paper release mechanism is usually provided on typewriting machines, which normally 20 presses collated sheets against the platen.

The present invention may in some forms dispense entirely with such paper release mechanism; or, may be used in conjunction therewith. In the latter event, simple mechanism is provided by this invention to automatically condition the 25 paper release mechanism, which in its preferred form is merely a link joining the line spacing or platen shifting lever to the control lever for the paper release mechanism.

It is another object of the present invention to 30 provide a writing machine of the above character in which the means for insuring a positive feeding of the collated sheets in alignment and registry is associated with the platen shifting or advancing means in such a way that it is moved 35 into operative position upon actuation thereof.

To this end there is provided as a feature of the invention a feeding means, preferably in the form of pins, mounted for movement toward and with the platen, and which is so connected with the platen shifting means that upon actuation of the latter the pin means is moved inwardly to pierce the sheets and then be carried with the platen during its rotating and sheet advancing movement. 45

Another feature of the invention resides in the provision of a locking means, preferably in the form of a pin or pins, which are normally in a position to pierce and lock the collated sheets to the platen, but which is connected with the platen shifting means to be moved to an inoperative position away from the platen upon actuation of the shifting means.

A further feature of the invention consists in so associating the pin locking and the pin feed-

ing means with the platen shifting means that the pin locking means is not withdrawn from the sheets until subsequent to the inward movement of the pin feeding means to pierce the sheets, thus insuring a positive maintenance of the collated sheets at all times in alignment and registry.

Another object of the invention is to provide a pin feeding means for insuring an advance of the collated sheets in alignment and registry which is readily adjustable to cooperate with sheets of various widths.

To this end there is preferably provided two pin carriers mounted on a shaft for rocking movement therewith to urge the pins toward the platen to pierce the collated sheets upon actuation of the platen shifting lever, one or both of the carriers being shiftable on the shaft axially of the platen for cooperation with wide and narrow sheets on the main platen.

Another object of the invention is to so actuate the pin feeding means that the lineal advance of the outer sheet or sheets of the collated forms is the same as that of the inner sheets.

25 In attaining the above object the pin means is so mounted that as it is carried with the platen upon the actuation of the platen shifting means the other portions of the respective pins are leaned backwardly to compensate for the difference in the radial distance between the axis of the platen and the inner and outer collated sheets which would normally cause a greater lineal travel of the outer sheets thus resulting in an uneven feeding.

Other and more specific objects and features will hereinafter appear.

In the drawings:

Figure 1 is a top view of a conventional typewriter carriage and platen showing one embodiment of my invention associated therewith.

Fig. 2 is an end view looking toward the right in Fig. 1 with a portion of the carriage removed to enable a clearer illustration.

Fig. 3 is an end view partly in section looking toward the left in Fig. 1.

Fig. 4 is a top view similar to Fig. 1 but showing a modification of the invention.

Fig. 13 is a top view similar to Figs. 1 and 4 but showing another modified form of the invention.

Fig. 14 is a partial sectional view taken on the line 14—14 of Fig. 13.

Fig. 14A is an enlarged fragmentary and sectional view of the pin structure disclosed in Fig. 14.

Fig. 15 is a detail view showing a modification of the pin feeding means disclosed in Fig. 14.

Although the several forms of the present invention are shown applied to a conventional typewriter of the form used for correspondence it will be understood that they are equally applicable on tabulating, bookkeeping, accounting and other machines where it is desirable to maintain and feed collated sheets or strips in registry.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring more particularly to the drawings and first to Figs. 1 through 3, there is shown for the purpose of illustration side frames 20 and 21 of a conventional typewriter carriage supporting in recesses 22 and 23 respectively in the upper faces thereof a rotatable shaft 24 carrying a platen roller 25 of rubber or the like upon which superposed collated sheets of record material, such for example as original sheet 26 and duplicate sheet 27 with a carbon paper 28 therebetween, may be typed. Fingers 29 and 30 secured to the frames 20 and 21 by screws 31 serve in a well known manner to confine the shaft 24 in the recesses 22 and 23 for rotation therein. Conventional turning knobs 32 are shown at either end of the shaft 24 for rotating the platen 25.

As is also conventional, there is disclosed a platen shifting lever 33, preferably in the form of a bell crank, pivotally carried on an extension 34 on the side frame 20 which through a suitable linkage is connected with a pawl 35 for engagement with a ratchet wheel 36 fixed on the shaft 24 to impart a step-by-step rotary movement to the platen 25 upon actuation of the platen shifting lever 33 in a counter-clockwise direction. Any suitable spring means may be provided to return the shifting lever 33 in a clockwise direction after the completion of the platen rotating movement.

Now of particular importance there is inserted between the shifting lever 33 and a link 37 pivotally mounted on the shaft 24 and carrying the pawl 35, a link 38 adapted to support and carry inwardly therewith during the initial movement of the shifting lever and before the pawl 35 engages the ratchet wheel 36 a pin feeding means 39 which is pressed through the collated sheets or forms and pricks into the platen 25. The mounting of the pin feeding means is such that after a pin 40 associated therewith has pierced the collated sheets during the initial movement of the shifting lever 33, the rotation of the platen 25 by the subsequent movement of the shifting lever 33 causes the pin 40 to rotate therewith to lock the collated sheets to the platen and positively feed the same without slippage or shifting of the collated superposed sheets 26 and 27 relative to each other.

In thus associating the pin feeding means 39 with the platen shifting lever 33 to provide the

advantageous feeding of the record sheets above described there is formed in the link 38 a channel 41 extending longitudinally thereof for receiving a slide block 42 having a depending arcuate portion 43 with a curvature substantially the same as that of the platen 25. Slidable association between the block 42 and the link 38 is maintained by a washer 44 secured to the block 42, as by a screw 45, and lapping the side of the link opposite the one adjacent the depending portion 43. A spring 46 connected to the link 38 and the slide block 42 normally maintains the latter at the left in the channel 41 as viewed in Fig. 2. Hence, with the construction just described the slide block is movable with the link 38 but is slidable to the right in the channel 41 against the tension of the spring 46.

Associated with the depending portion 43 of the block 42 and slidable upwardly and downwardly thereon is a carrier block 47 supporting the piercing pin 40 of the pin feeding means to extend inwardly toward the platen. Proper association and arcuate movement of the carrier block 47 on the depending portion 43 is achieved by forming beveled side walls 48 and 49 on the depending portion which are received in a groove 50 in the carrier block 47. A stop flange 51 at the lower end of the depending portion limits the downward movement of the carrier block on the depending portion and a spring 52 normally maintains the carrier in this lowered position as shown in Fig. 2. Thus, it is seen that when the pin feeding means is in an inoperative position spaced from the platen, as shown in Figs. 1 and 2, the slide block 42 is maintained at the left in the channel 41 and the pin 40 and the carrier block 47 are maintained in a lowered position on the depending portion 43.

In the operation of the pin feeding means 39, as will be readily understood from the drawings and the above description, when the shifting lever 33 is moved in a counter-clockwise direction the carrier block 47 and pin 40 are initially moved inwardly so that the pin pierces the collated sheets and locks the same relative to each other and to the platen. Subsequent movement of the shifting lever and link is permitted by the spring 46 which permits the link 38 to move relatively to the slide block to cause platen rotating engagement between the pawl 35 and the ratchet wheel 36.

During the rotation of the platen 25 the carrier block 47 which is locked thereto by the pin 40 is caused to slide upwardly on the depending portion 43 and to thus positively lock the collated sheets to prevent relative movement therebetween during the entire rotary movement of the platen and to effect simultaneous movement of the collated sheets with the platen.

Upon a completion of the platen shifting movement and upon a movement of the shifting lever in a clockwise direction, as by any movable spring means, the carrier block 47 and pin 40 are moved away from the platen and then caused to return to the initial lowered position by the spring 52.

Preferably, in addition to the pin feeding means 39 at the left hand end of the carriage, as viewed in Fig. 1, there is also provided at the right hand end of the carriage a second and similar pin feeding means 53 pivotally associated with the side frame 21 to be moved inwardly toward the platen upon an actuation of the shifting lever 33. The structure for thus pivotally supporting the pin feeding means 53 includes a rod 54 pivotally mounted in the right side frame 21 as by passing through a hole 55 therein and prevented from

dropping out of the frame by a pin 56. An arcuate guide portion 57 similar to the arcuate portion 43 at the left hand side of the carriage is rigidly connected to the pivot rod 54 as by an intermediate rod 58 having a screw threaded connection with the lower end of the pivot rod 54 and a like connection with a flange portion 59 at the lower end of the arcuate guide portion 43. As with the feeding means at the left hand side of the carriage, the feeding means 53 includes a carrier block 60 carrying a piercing pin 61 and formed with a groove 62 to receive the beveled side walls 63 and 64 of the arcuate guide portion 57. Also as with the feeding means 39 at the left hand side of the carriage, the carrier block 60 while slidable upwardly and downwardly on the arcuate guide portion is normally maintained in a lowered position against the flange 59 by a spring 65.

In order that the pin feeding means 53 may be operated concurrently with the feeding means 39 upon the actuation of the shifting lever 33 there is formed on the side of the pawl 35 a cam 66 which, upon a counter-clockwise movement of the shifting lever 33 engages one end of a rod 67 carried in a hollow shaft 68 pivotally associated with the side frames 20 and 21, as by arms 69 and 70 respectively mounted on rigid supporting arms 71 and 72, to urge the rod to the right to engage a laterally extending portion 73 of the pivotally mounted rod 54 and cause the latter to move in a clockwise direction to push the piercing pin 61 through the superposed collated sheets 26 and 27. Hence, the piercing pin 61 is caused to pierce the collated sheets concurrently with the pin 40 at the left hand side of the carriage and is likewise concurrently carried upwardly with the platen during the entire rotary movement thereof. If preferred, preformed holes 25' may be provided in the platen for the feeding pins to enter.

Upon a completion of the platen advancing movement the pawl 35 and cam 66 move to their initial position, thereby releasing the rod 67 and permitting a spring 74 connected to the right side frame 21 to swing the piercing pin carrying rod 54 in a counter-clockwise direction, thus releasing the piercing pin from the collated sheets and the platen and permitting the spring 65 to draw the pin carrier block 60 to a lowered position on the arcuate guide portion 57. A stop screw 75 on the side frame 21 is engageable with the cross pin 56 to limit the counter-clockwise movement of the pivotally mounted rod 54.

With the above construction the advantageous pin feeding means of the present invention is normally maintained in a retracted and inoperative position but is moved into an operative position concurrently with the actuation or initial movement of the platen shifting means to pierce the collated sheets and lock the same on the platen to prevent relative movement therebetween during the entire feeding operation.

Paper holding and feeding rollers 76 on the pivotally mounted hollow shaft 68 prevent the forward ends of the sheets from falling forwardly and serve to hold the collated sheets relative to each other and to the platen during the typing operation. If desired, as when it is wished to adjust the collated sheets relative to the platen, the bail 77 comprising the arms 69 and 70 and the hollow shaft 68 may be swung upwardly into a retracted position near the top or back of the machine without disconnecting any of the parts as the rod 67 is of such a length that it drops between the cam 66 and the later-

ally extending portion 73 of the pivotally mounted rod 54 when it is swung into the lowered position, as shown in Fig. 1. A spring 78 is provided, connected to one of the pivotally mounted arms 69 and the rigid supporting arm 71 therefor to yieldingly maintain the paper holding and feeding rollers in a lowered position.

Feeding and locking type

- 10 In the modification disclosed in Figs. 4, 5, 6, 7 and 8 there is provided a pin means 79 for locking the collated sheets intermediate the platen shifting operations as well as a pin means 80 co-operable to feed the collated sheets in alignment and registry during the platen shifting operation.

15 As in Fig. 1, there is illustrated in Fig. 4 side frames 20 and 21 of a conventional typewriter carriage supporting a platen 25 of rubber or the like. Also as in Fig. 1 and as is conventional there is included the shifting lever 33 for operating the pawl 35 to engage with the ratchet wheel 36 to impart a step-by-step rotary movement to the platen. Likewise, there is provided a bail 25 81 pivotally associated with the side frames 20 and 21 by arms 82 and 83 pivotally mounted on the rigid supporting arms 71 and 72 to be swung upwardly and into a retracted position at the back of the machine. However, a shaft 84 rotatably 30 carried between the arms 82 and 83 of the bail 81 is formed with a slot 85 extending longitudinally thereof and carries a sleeve 86 with a slot 87 likewise extending longitudinally thereof for purposes that will hereinafter be explained in 35 detail.

Now of particular importance the pin locking means 79 includes a block 88 having a hub portion 89 encircling the sleeve 86 and locked to the shaft 84 for movement therewith by a screw 90 in threaded relation with the block and extending freely through the slot 87 in the sleeve and into the narrower slot 85 in the shaft 84. The locking pin 91 is fixed in the underface of a rearwardly extending finger 92 on the block 88.

40 For normally maintaining the locking pin 91 in an operative relation with the collated sheets and the platen 25 when the paper lock bail 81 is in a lowered position and supported on the platen by the rollers 76, as shown in Figs. 4 and 5, there is provided a flat spring 93 secured to one of the arms 82 of the bail 81 as by screws 94 and entering a slot 95 in the end of the shaft 84. This flat spring 93 thus serves to yieldingly maintain the locking pin 91 in operative position when the bail 81 is moved into a lowered position under the tension of springs 96 interposed between the pivotally mounted arms 82 and 83 and the supporting arms 71 and 72 respectively. In order that the bail 81 may normally be pulled down into 45 fully operative position, as shown in Fig. 5, with the rollers 76 resting on the collated sheets the spring 93 is made of a lighter tension than the combined pull of the springs 96 which are stronger than usual bail springs. Thus when the bail 50 81 is moved into a lowered position with the pin 91 piercing the collated sheets and pricking the platen 25 the spring 93 permits the block 88 to be moved slightly under the influence of the springs 96 until the rollers 76 rest on the collated sheets.

55 70 Associated with the pin locking means 79 is a pin feeding means 80 including a block 97, preferably made of two sections 98 and 99 secured together with screws 100, formed with a bifurcated hub portion 101 encircling the sleeve 86 on both sides of the block 88 and formed with a forward-

ly extending arcuate guide portion 102 which supports a slideable feeding pin 103 adapted to pierce the collated sheets and hold them from slippage relative to each other during the rotation of the platen.

5 Preferably, and as disclosed, the feeding pin 103 is mounted in a carrier 104 slideable in an arcuate guideway 105 in the forwardly extending portion 102 of the block 97. Balls 106 in the guideway serve to permit free sliding movement of the carrier 104 while a pin 107 extending through slots 108 in the sides of the block serve to maintain the carrier in proper association with the guideway.

10 For connecting the block 97 to the rotatable sleeve 86 there are provided in suitable channels 109 in the bifurcated hub portion 101 one or more springs 110 with one end 111 suitably secured to the sleeve 86 in a slot 112 extending longitudinally thereof and with the opposite end 113 pressing 20 against an end wall 114 of the channel.

15 In order that the sleeve 86 may normally be urged in a clockwise direction about the shaft 84 with the side wall 115 of the slot 87 engaging the screw 90 and the pin 103 maintained in a 25 raised and inoperative position as shown in Fig. 5 there is provided a spring finger 116 secured to the sleeve 86 at its upper end as by a yoke and screw connection 117 and connected at its lower end with the platen shifting lever 33.

20 Preferably, and as shown, this latter connection is provided by a pin 118 secured to an angle plate 119 on the shifting lever which enters a slot 120 at the lower end of the spring finger. This connection is advantageous in that it permits free movement of the bail 81 to an upper retracted position without the use of tools or any special adjustments. Moreover, it permits a likewise free return of the bail to a lowered and operative position.

25 In the operation of this form of the invention after the collated sheets have been properly positioned relative to the platen the bail 81 is swung from a retracted position into an operative position over the platen, as shown in Figs. 4 and 5, in which position as heretofore explained the locking pin 91 pierces the collated sheets to maintain them from movement relative to each other and slightly pricks into the platen 25.

30 When it is desired to shift the platen and the collated sheets thereon it is merely necessary to actuate the platen shifting lever 33 in the conventional manner whereupon the spring finger 116 connected to the shifting lever through pin 118 and slot 120, as best seen in Figs. 5 and 8, is moved in a counter-clockwise direction to push the feeding pin 103 through the collated sheets and into the platen. During this movement the block 88 and locking pin 91 remain in an operative position relative to the platen as permitted by the slot 87 and spring 110. However, after the feeding pin 103 has been moved into an operative position relative to the platen the side wall 121 of the slot engages the screw 90 to turn the shaft 84 and associated block 88 35 in a counter-clockwise direction against the tension of the flat spring 93 to move the locking pin 91 upwardly from the platen and collated sheets just prior to the actual engagement of the pawl 35 with the ratchet wheel 36 to rotate 40 the platen. This delayed movement of the locking pin is made possible by the slot 87 and the yielding spring 110 between the block 97 and the sleeve 86 which permits further rotation of the sleeve after movement of the feeding pin 103.

has been arrested by its engagement with the platen.

With the feeding pin thus moved to an operative position and yieldingly maintained therein by the spring finger 116 and the spring 110, further movement of the shifting lever 33 causes the platen 25 to rotate and carry therewith during its entire rotary movement the feeding pin 103 which is slidably supported by the arcuate guide portion 102 and thus serves to positively lock the collated sheets relative to each other and to the platen during the entire feeding operation. Because of the fact that the feeding pin is movable by and with the platen it serves equally well to lock the collated sheets whether the platen shift be one line or more than one line.

Upon a completion of the platen shifting movement, the shifting lever 33 is permitted to return to its retracted position in the normal manner. The sleeve 86 is turned in a clockwise direction to move the side wall 121 of the slot 87 away from the screw 90 which permits the shaft 84 under the influence of the spring 93 to likewise turn in a clockwise direction to urge the locking pin 91 once more through the collated sheets and into the platen. During this initial rotation of the sleeve 86 the block 97 is maintained stationary with the feeding pin 103 in an upward position and in engagement with the platen due to the expansion of the spring 110 which was compressed during the movement of the locking pin 91 away from the platen. Subsequent movement of the sleeve causes the arcuate portion 102 to be moved away from the platen and permits the carrier block 104 and the feeding pin 103 to return to their initial position at the lower end of the guideway 105.

From the foregoing it will be seen that the collated sheets are at all times locked relative to each other and to the platen by either the locking pin 91 or the feeding pin 103, thus insuring the maintenance of the collated sheets in alignment and registry. If desired, however, a finger 122 may be secured to the shaft 84 to move the locking pin 91 to a raised position independently of the movement of the platen shifting lever in order to permit the collated sheets to be moved into proper registry or to be pulled from the machine without raising the paper lock bail 81. This latter feature is desirable when the usual paper release mechanism is employed and when it is desirable to rotate the platen and sheets thereon with the knobs 32.

Preferably and as shown, there are associated with the shaft 84 and sleeve 86 two pin feeding and pin locking means 80 and 79 respectively of the character described in order that positive locking of the collated sheets may be attained adjacent both marginal edges thereof. Of special importance it is to be noted, because of the longitudinal extending slots 87 and 111 in the sleeve 86 and a like extending slot 85 in the shaft 84, it is possible by loosening the screw 90 to shift either or both of the two pin feeding and locking means axially of the platen to cooperate with the marginal edges of sheets of various widths.

Gear and rack type

In Figs. 9 and 10 there is disclosed a slightly modified form of connection between the platen shifting lever 33 and the shaft 84. It includes a rack 123 secured to the shifting lever 33, as by screws 124, which cooperates with a gear 125 on the sleeve 86 to rotate the latter concurrently

with the platen shifting operation. A spring 126 secured at one end to a collar 127 fixed to the sleeve 86 by a set screw 128 and at the other end to the gear 125, serves to achieve the desirable yielding effect of the spring finger 116 shown in Figs. 4 through 8. A stop pin 129 on the gear 125 and engageable with the collar 127 limits the yield between the latter two members.

This connection while permitting a free movement of the bail 81 to a retracted position is more costly than the connection first described and is somewhat less advantageous.

Simplified form

15

In Figs. 11 and 12 a simplified one-piece structure is disclosed for supporting the feeding pin 103 and locking pin 91. It includes a block 130 having a hub portion 131 fixed to a shaft 132 by a screw 133 and provided with a rearwardly 20 extending finger 135 for mounting the locking pin 91 and with a forwardly extending arcuate portion 136 for supporting the feeding pin 103. Preferably, as shown, the arcuate portion is made of two sections 137 and 138 secured together by 25 screws 139 to facilitate manufacture.

As with the preferred form disclosed in Figs. 4 through 8 the forwardly extending portion 136 has formed therein an arcuate guideway 140 of substantially the same curvature as the platen 30 for guiding a feeding pin carrier block 141 during the rotation of the platen 25 and after the feeding pin 103 has been moved inwardly to pierce the collated sheets. Also, as in Figs. 4 through 8, balls 142 are provided to facilitate the sliding of 35 the carrier block, and a pin 143 is provided passing through slots 144 in the sides of the arcuate portion 136 serve to maintain the carrier block in the guideway.

With the modified one-piece block 130 the use of the slotted sleeve 86 is eliminated, the connection being directly to the shaft 132, and there is no delayed action between the locking pin 91 and the feeding pin 103. Hence, upon a rotation of the shaft 132 during the initial movement of the platen shifting lever 33 the locking pin 91 will be out of the collated sheets for a very short period of time just prior to the moving of the feeding pin 103 into the sheets. In all other particulars the operation of the modified pin feeding and locking means is essentially the same as in the preferred two part form. Like in the preferred form, it is preferable to utilize two pin feeding and locking means mounted for movement axially of the platen to enable adjustment for cooperation with the marginal edges of sheets of different widths.

Differential type aligning device

When a large number of sheets are on the platen there is danger of the outer sheets traveling a greater extent than the inner sheets.

The forms of the invention disclosed in Figs. 13, 14 and 15 are closely related to the form disclosed in Figs. 4 through 8. However, in these modifications the feeding pin 155 is so supported and guided during its movement with the platen that exactly equal lineal feed of all of the superposed and collated sheets is achieved.

As in Fig. 4 there are shown in Fig. 13 side frames 20 and 21 of a conventional typewriting carriage, supporting for rotation a platen 25 of rubber or the like. Likewise as in Fig. 4 the longitudinally slotted sleeve 86 and the longitudinally slotted shaft 84 are carried between pivotally

mounted arms 145 and 146 and are associated with each other and with the platen shifting lever 33 to be rotated during the platen shifting operation. Rollers 76 support the shaft 84 and sleeve 86 relative to the collated sheets and to the platen when the paper lock bail 147 is in a lowered position.

The structural differences between the modified form in Figs. 13 and 14 and the form in Figs. 10 4 through 8 for achieving the advantageous guiding of the feeding pin 155 during the rotation of the platen include the provision of a pair of links 148 and 149 pivoted on pins 150 and 151 on each of the arms 145 and 146 and provided at their 15 forward ends with rods 152 and 153 extending axially of the platen to support carrier blocks 154 for feeding pins 155. Preferably, and as shown, the carrier blocks 154 are formed with holes to receive the rods 152 and 153 to properly space 20 the latter relatively to each other. However, any suitable confining and locating means may be used for this purpose.

For moving the feeding pins 155 into the collated sheets upon an actuation of the platen shifting lever and subsequent to the moving of the locking pins 91 to a raised and inoperative position there is provided for each of the feeding pin carriers 154 a block 156 having a bifurcated hub portion 157 associated with the sleeve 86 25 and the locking pin block 88 in the same manner as the block 97 in Figs. 4 through 8. However, in the modified block 156 the forwardly extending portion is in the form of a finger 158 adapted to overlie the pin carrier block 154 and 30 is provided with a laterally extending stop flange 159 at its lower end for supporting the feeding pin carrier block 154 in the retracted and inoperative position shown in Fig. 14.

With the above construction when the sleeve 40 86 is rotated by the shifting lever 33 the finger portion 158 is moved in a counter-clockwise direction to engage the upper end of an enlarged shank portion 160 of the feeding pin 155 to push the latter relatively to the carrier block 154 and 45 through the collated sheets to prick the platen 25. For permitting movement of the pin 155 relatively to the carrier 154 while at the same time maintaining the pin in proper relation therewith there is formed in the carrier a guide bore 161 50 having an internal shoulder 162 engageable with a shoulder 163 on the enlarged shank 160 to prevent the pin from falling out of the carrier.

Upon rotation of the platen 25 by the engagement of the pawl 35 with the ratchet wheel 36 in 55 the well known manner the feeding pin 155 and carrier 154 are moved with the platen in the same general manner as in the form disclosed in Figs. 4 through 8. However, because of the links 148 and 149, the feeding pin 155 is leaned backwardly as it is carried upwardly with the platen in such a way that the outer end of the pin travels the same peripheral distance as the inner end of the pin. In this manner compensation is 60 made for the difference in radial distance between the axis of rotation of the platen 25 and the inner and outer collated sheets which would normally cause a greater lineal travel of the outer sheets and thus result in uneven feeding.

In order that the pin 155 may be maintained 70 in piercing relation with the collated sheets during rotation of the platen a guide channel 164 is formed in the finger and provides a back guide wall 165 which engages the upper end of the enlarged shank portion 160 and urges the pin 155 toward the platen as it moves therewith. Prefer-

ably a spring 166 is positioned in the guide bore 161 intermediate the shoulder 162 and the enlarged shank portion 160 to yieldingly maintain the end of the enlarged shank portion 160 of the pin 155 in contact with the back guide wall. 5 Any needed yield of the pin 155 relative to the platen during rotation of the latter is afforded by the spring finger 116 with which the shifting lever 33 is connected to the sleeve 86 and by the yielding spring connection between the sleeve 86 10 and the hub portion 157 of the block 156.

When the platen shifting operation is completed the sleeve 86 through its connection with the shifting lever 33 is turned in a clockwise direction causing the locking pin 91 to pierce the 15 collated sheets. Concurrently it causes the depending finger 158 to move outwardly to permit the feeding pin 155 and carrier block 154 to swing outwardly and downwardly to the inoperative position shown in Fig. 14.

As in the form disclosed in Figs. 4 through 8, one or both of the two pin feeding and pin locking means may be adjusted longitudinally of the platen to cooperate with collated sheets of different widths by merely loosening the screws 90 25 with which the blocks 156 and 88 are clamped to the shaft 84.

In the modified construction disclosed in Fig. 15 for insuring, as does the feeding means of Figs. 13 and 14, an equal lineal feed of all of the super- 30 posed collated sheets a modified block 167 is provided for supporting a feeding pin 168. As in the block 97 disclosed in Figs. 4 through 8 the modified block is formed with a bifurcated hub portion 169 encircling the slotted sleeve 86 and the 35 slotted shaft 84. Similarly to the block 97, the modified block 167 is provided with a depending portion 170 having a guideway 171 for a feeding pin carrier block 172.

In the modified block 167, however, slots 173 40 in the side walls of the depending portion 170 serve as a cam track for a pair of pins 174 on the carrier 172 to lean the latter backwardly relatively to the platen as it slides in the guideway 171 during the feeding of the collated sheets. A 45 cam surface 175 provided by the back wall of the guideway and engageable with the carrier block 172 supplements the cam track 173 in leaning the carrier block backwardly relatively to the platen during rotation of the latter. The cam track 173 50 and cam surface 175 which thus cause the pin carrier 172 to lean backwardly are so shaped that equal lineal travel of the outer and inner ends of the feeding pin is achieved.

A spring 176 positioned in a guide bore 177 in 55 the carrier block 172 and cooperable with the cam surface 175 at one end and engageable with a head 178 on the feeding pin 168 at the other end maintains the pin in piercing relation with the collated sheets and in contact with the platen 60 during its rotation upon actuation of the shifting lever. An internal shoulder 179 in the guide bore 177 prevents the pin 168 from falling out of the carrier when the latter is in a retracted position.

With this modified feeding means, therefore, it is seen that after the depending portion 170 of the block 167 is moved in a counter-clockwise direction to force the pin 168 through the collated sheets and into the platen, that as the feeding pin 70 168 is carried upwardly with the platen it is leaned backwardly with the carrier 172 under the influence of the cam track 173 of predetermined curvature so that its peripheral travel is the same throughout its length. Hence, as with the

link controlled feeding pin of Figs. 13 and 14, each of the superposed collated sheets is advanced an equal lineal distance each time the platen is shifted.

Upon a rotation of the sleeve 86 in a clockwise direction when the platen shifting lever 33 is returning to its normal position, the depending portion 170 is moved away from the platen in the same manner as the depending portion 102 in Figs. 4 through 8 and the feeding pin carrier 172 drops by gravity to its initial position at the lower end of the guideway 171. If desired any suitable spring may be provided to aid in returning the carrier 172 to its lower position.

Under normal conditions the pin feeding means of Figs. 4 through 8 function in a highly satisfactory manner to feed the collated sheets in aligned and registering relation. Where a plurality of sets of continuous forms are to be fed through a machine, however, it may be advantageous to utilize the special feeding means of Figs. 13 and 14 or that shown in Fig. 15.

As shown in Fig. 1, in which form its inclusion is especially advantageous, there may be provided with each of the forms of the invention a means controlled by the platen shifting lever for moving the usual small pressure rollers underlying the platen to a material releasing position. In the preferred embodiment illustrated, this means includes an L-shaped spring arm 180 with an intermediate bowed portion 181, extending between and secured to the shifting lever 33 and a usual pressure release handle 182 with which all standard typewriters are equipped.

With this construction the handle 182 is moved to release the pressure rollers during initial movement of the shifting lever 33. Subsequent and platen rotating movement of the shifting lever is permitted by the flexing of the spring arm. Return of the shifting lever moves the handle 182 to pressure locking position. Hence, while the pressure rollers are normally maintained in operative position to hold the record material beneath the platen, they are automatically moved to a releasing position to prevent a drag on the sheets of record material during the platen rotating and material feeding operation. In the illustration given, the releasing handle 182 is so associated with the pressure rollers that a rearward movement thereof is required to release the pressure rollers. If the handle is such that forward movement is required to release the pressure rollers it is merely necessary to reverse the L-shaped arm, as shown in dotted lines, so that its operative axis lies on the other side of the pivotal axis of the shifting lever.

A further device for automatically moving the usual pressure rollers to a material releasing position is shown in Fig. 5. Like the pressure release control illustrated in Fig. 1, this control may be advantageously provided with each of the forms of the invention.

This modified control means, unlike the one first described, is operable upon movement of the paper lock bail 81 to a lower and operative position. It includes a cam 183 on an arm 82 of the bail 81 which engages a projection 184 on the usual pressure release handle 182 to cause the latter to move to a pressure releasing position. Thus, when the bail 81, and also the pin means in Figs. 4 through 15, are swung to operative position the usual pressure rollers are automatically moved away from the platen to prevent any adverse drag on the material during the actuation of the pin feeding means.

Variations and modifications may be made within the scope of this invention and portions of the improvements may be used without others.

Having thus described the invention what is claimed as new is:

1. In a device of the character described the combination of a platen for supporting superposed sheets; feeding means engageable with said sheets, and movable by and with said platen; locking means for said sheets on said platen; control mechanism for rotating the platen; and means operated by said control mechanism for rendering said locking and said feeding means respectively inoperative and operative.

2. In a device of the character described the combination of a platen for supporting superposed sheets; feeding means engageable with the sheets, and movable by and with said platen; locking means for said sheets; control means for rotating the platen; and means for rendering the feeding means operative and the locking means inoperative as the control means is operated in one direction, and for rendering the feeding means inoperative and the locking means operative as the control means is operated in the opposite direction.

3. In a device of the character described the combination of a platen; feeding pin means mounted for movement toward and with said platen; and a single means for moving said pin means into operative engagement with said platen while the latter is stationary and then subsequently rotating the platen to carry the feeding means therewith.

4. In a device of the character described the combination of a platen; locking means normally maintained in operative engagement with said platen; feeding means mounted for movement toward and with said platen; and means for moving said locking means and said feeding means respectively out of and into operative engagement with said platen and then subsequently rotating the latter to carry the feeding means therewith.

5. In a device of the character described the combination of a platen; locking means normally maintained in operative engagement with said platen; feeding means mounted for movement toward and with said platen; and means for successively moving said locking means and said feeding means respectively out of and into operative engagement with said platen and then subsequently rotating the latter to carry the feeding means therewith.

6. In a device of the character described the combination of a platen for supporting a writing sheet; feeding means for said writing sheet, having a retracted and an advanced position; and means for maintaining said feeding means in operative engagement with said platen and said sheet to be moved from said retracted to said advanced position simultaneously with the platen and solely thereby during rotation thereof.

7. In a device of the character described the combination of a platen for supporting a writing sheet; locking means for said sheet, having operative and inoperative positions; feeding means for said sheet having operative and inoperative positions; control means for moving said platen, having normal and advancing positions, adapted when in said normal position to maintain said locking means and said feeding means respectively in operative and inoperative positions, when in said advancing position to maintain said locking means and said feeding

- means respectively in their inoperative and operative positions, and at predetermined intervals to maintain both the feeding and the locking means in operative position.
5. 8. In a device of the character described the combination of a platen for supporting a writing sheet; control means for rotating said platen; locking means; feeding means; means for locating said locking means and said feeding means in divers positions longitudinally of said platen; and means for moving said locking means and said feeding means respectively out of and into operative engagement with said platen concurrently with the operation of said control means.
10. 9. In a device of the character described the combination of a platen; locking and feeding mechanism including locking means and feeding pin means, having operative and inoperative locations respectively adjacent to and remote from said platen; control means for operating said platen and for moving said locking means and feeding pin means toward and away from said platen when said locking and feeding mechanism is in said operative location; and a connection between said control means and said locking and feeding mechanism permitting free movement of the latter into and out of said operative location.
15. 10. In an apparatus of the class described the combination of a main platen upon which a plurality of sheets may be typed; platen shifting means; means for feeding the sheets, normally disconnected from said platen; and means controlled by said shifting means for moving said feeding means toward and into operative engagement with said platen to be advanced therewith and solely by said engagement.
20. 11. In an apparatus of the class described the combination of a main platen upon which a plurality of sheets may be typed; platen shifting means; means for normally locking said sheets; means for feeding said sheets; and means controlled by said shifting means, for moving said locking and said feeding means respectively out of and into operative engagement with said platen.
25. 12. In an apparatus of the class described the combination of a platen upon which a plurality of sheets may be typed; a platen shifting means; a pin means mounted for movement toward and then with said platen; guide means movable from a retracted position to force said pin means through said sheets and into engagement with said platen upon initial movement of said platen shifting means and to maintain said pin means in engagement with said platen to be moved therewith during subsequent and platen rotating movement of said shifting means; and means for operatively associating said platen shifting means and said guide means.
30. 13. In an apparatus of the class described the combination of a main platen upon which a plurality of sheets may be typed; a platen shifting means; a link in said shifting means; a guiding and supporting means movable with and slideable relatively to said link; yielding means for normally urging said guiding and supporting means toward said platen on said link; and pin means carried by and slideable on said guiding and supporting means, said pin means being movable with said guiding means from a normal retracted position toward said platen to engage the latter and pierce said sheets during the initial movement of said shifting means and being movable by and with said platen on said guiding means during the subsequent and platen rotating movement of said shifting means.
35. 14. In an apparatus of the class described the combination of a platen for supporting sheets; a platen shifting means; pin feeding means; pressure means for maintaining the sheets in engagement with said platen and movable from a normal operative to a releasing position; means operated by said platen shifting means for moving said pressure means from the operative to the releasing position upon actuation of said shifting means; and means for moving said pin means into an operative position upon actuation of said shifting means.
40. 15. In an apparatus of the class described the combination of a platen for supporting sheets; a platen shifting means; pin feeding means; pressure means for maintaining the sheets in engagement with said platen and movable from a normal operative to a releasing position; a paper lock bail movable from a raised inoperative to a lowered operative position relative to said platen; means for moving said pressure means from the operative to the releasing position upon movement of said bail to its operative position; and means controlled by said shifting means for moving said feeding pin means into an operative relation with said platen.
45. 16. In an apparatus of the class described the combination of a main platen upon which a plurality of sheets may be typed; a platen shifting means; means for normally locking said sheets; means for feeding said sheets; means controlled by said platen shifting means for moving said locking means away from and into inoperative relation with said platen and for moving said feeding means toward and into operative relation with said platen; and means independent of said platen shifting means for moving said locking means away from said platen.
50. 17. In an apparatus of the class described the combination of a main platen roller upon which superposed sheets may be typed; a platen shifting means; pin means mounted for movement toward and then with said platen to cooperate therewith for feeding said sheets; means connected with said shifting means for moving said pin means toward and into an operative relation with said platen upon actuation of said platen shifting means; and means for guiding said pin feeding means during its movement with said platen to cause substantially equal lineal movement of said superposed sheets.
55. 18. In a device of the character described the combination of a platen for supporting a plurality of superposed sheets; a feeding pin mounted for movement toward and with said platen; means for forcing said feeding pin through said sheets into operative engagement with said platen and for subsequently rotating the latter to carry the feeding pin therewith; and means for guiding said feeding pin during its movement with the platen to achieve equal sheet advancing movement thereof throughout its length.
60. 19. In a device of the character described the combination of a rotatable platen for supporting a sheet; pin feeding means movable toward, with and from said platen; means for normally maintaining said pin feeding means away from said platen; and means for moving said pin feeding means toward said platen to pierce said sheet and engage said platen to be carried forward therewith and solely thereby during its rotation, and for automatically moving said pin

feeding means away from said platen on completion of the rotation of the platen.

20. In a device of the character described the combination of a rotatable platen for supporting a sheet relative to a printing line; pin feeding means; means for normally maintaining said pin feeding means away from said platen; and means for moving said pin feeding means to pierce said sheet and engage said platen prior to the rotation thereof, for maintaining the pin feeding means in engagement with said platen to be moved therewith and solely thereby from a retracted to an advanced position on the rotation thereof, and for moving said pin feeding means away from said platen subsequent to the rotation thereof to return the same from the advanced to the retracted position.

21. In a device of the character described the combination of a platen for supporting writing material; a pair of pin feeding means spaced longitudinally of the platen and movable toward and with said platen; means for normally maintaining said pin feeding means away from said platen; and interconnected means for moving said pin means to pierce said sheets and engage said platen and for subsequently rotating said platen to advance the pin feeding means solely through its engagement therewith.

22. In an apparatus of the class described the combination of a platen for supporting sheets; a platen shifting means; pin feeding means; pressure means for maintaining the sheets in engagement with said platen and movable from a normal operative to a releasing position; a paper locking bail movable from a raised inoperative to a lowered operative position relative to said platen; means for moving said pressure means from the operative to the releasing position upon movement of said bail to its operative position; and means for moving said pin means into an operative position upon actuation of said shifting means.

22. In an apparatus of the class described the combination of a main platen upon which a plurality of sheets may be typed; platen shifting means; a pair of pin feeding means spaced longitudinally of said platen and cooperable therewith for feeding said sheets; means for normally maintaining said pin feeding means away from said platen; means for adjusting at least one of said pin feeding means longitudinally of said platen; and means for moving the pin feeding means toward said platen to pierce said sheets and engage said platen to be advanced therewith and solely thereby upon actuation of said platen shifting means.

24. In an apparatus of the class described the combination of a platen upon which a plurality of sheets may be typed; platen shifting means; pin feeding means mounted for movement toward and then with said platen; and means including a spring member for connecting said

shifting means and said pin feeding means for moving the latter during initial movement of said shifting means to pierce said sheets and engage said platen to be moved by and with said platen during subsequent and platen rotating movement of said shifting means.

25. In a device of the character described the combination of a platen; feeding pin means engageable with said platen; locking pin means engageable with said platen; control means for rotating the platen; and means for rendering the feeding pin means operative and the locking pin means inoperative as the control means is operated in one direction, and for rendering the feeding pin means inoperative and the locking pin means operative as the control means is operated in the opposite direction.

26. In an apparatus of the class described the combination of a main platen upon which a plurality of sheets may be typed; platen shifting means; locking means for said sheets; pin feeding means mounted for movement toward and then with said platen; and means for successively moving said pin feeding means into operative engagement with and said locking means away from said platen during initial movement of said platen shifting means, whereby upon subsequent and platen rotating movement of said platen shifting means the pin feeding means is carried by and with said platen.

27. In a device of the character described the combination of a platen; locking means normally maintained in operative engagement with said platen; pin feeding means movable toward and then with the platen; platen shifting means; and means for moving said locking means and said feeding means respectively out of and into operative engagement with said platen and then subsequently rotating the latter to carry the feeding means therewith when the shifting lever is moved in one direction and for moving said locking means and said feeding means respectively into and out of operative engagement with the platen when the platen shifting means is moved in the other direction.

28. In a device of the character described the combination of a rotatable platen for supporting a sheet; pin feeding means movable toward, with and from said platen; pin means for locking said sheets and movable toward and away from said platen; and means for moving said pin feeding means and said pin locking means respectively toward and away from said platen to engage and disengage said sheet prior to the rotation of said platen, whereby upon rotation of the platen the feeding pin means is advanced therewith and thereby, and for moving said pin feeding means and said pin locking means respectively away from and toward said platen to disengage and engage said sheet subsequent to the rotation of said platen.

BEULAH LOUISE HENRY.

CERTIFICATE OF CORRECTION.

Patent No. 2,187,900.

January 23, 1940.

BEULAH LOUISE HENRY.

It is hereby certified that error appears in the printed specification of the above numbered patent requiring correction as follows: Page 8, first column, line 51, claim 12, after the word "position" insert toward said platen; line 56, same claim, after "therewith" insert and solely thereby: page 9, first column, line 2, claim 19, for "rotation of the platen" read feeding movement; and that the said Letters Patent should be read with this correction therein that the same may conform to the record of the case in the Patent Office.

Signed and sealed this 12th day of March, A. D. 1940.

Henry Van Arsdale,
Acting Commissioner of Patents.
